William S. Beeman

UNITED STATES PATENT OFFICE.

WILLIAM S. BEEMAN, OF ASHLAND, WISCONSIN, ASSIGNOR OF ONE-HALF
TO BIRGE W. DAVENPORT, OF SAME PLACE.

OILER FOR WRIST-PINS.

SPECIFICATION forming part of Letters-Patent No. 349,137, dated September 14, 1886.

Application filed April 15, 1886. Serial No. 198,889. (No model.)

To all whom it may concern:

Be it known that I, WILLIAM S. BEEMAN, a citizen of the United States, residing at Ashland, in the county of Ashland and State of Wisconsin, have invented certain new and useful Improvements in Oilers for Wrist-Pins; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates especially to that class of lubricators which are attached to the cranks of steam-engines, and which are so arranged that the revolution of the crank will operate the lubricator and cause it to feed the lubricant to the crank.

It consists in certain novel features herein-after described, and pointed out in the claims.

In the accompanying drawings I have shown in Figure 1 a side elevation of my device as applied to a crank. Fig. 2 is a central vertical section. Fig. 3 is a plan view, and Fig. 4 is an enlarged detail view.

Referring to the drawings by letter, A designates the cylinder which holds the lubricating material. It is provided at its lower end with a screw-threaded nozzle, A', which is screwed into the pitman-head, thereby securing the lubricator in position, and is made of such a length that when screwed home it will just touch the crank, as clearly shown in Fig. 2. This cylinder A is provided with a top or cover, A², which is held upon it by set-screws A³. A piston, B, working in the cylinder, is provided with a screw-threaded piston-rod, B', which works through the cover A², and is provided at its upper end with a hand-wheel, B², by means of which the piston is raised when so desired, as will be hereinafter fully described. A plate, C, provided with two upright posts, C', is secured upon the top of the cover A² by screws or other similar means, and a worm-gear, D, is journaled in these posts. This worm-gear shaft D is extended at one end, and upon this end extension I rigidly secure a ratchet-wheel, E. A sleeve, F, provided with an arm, F', is loosely mounted

upon this worm-gear shaft in juxtaposition to the ratchet-wheel E, the arm F' extending out past the circumference of the wheel. A pawl, F², is pivoted upon the arm F' near its outer end, and is held in engagement with the ratchet-wheel by a spring, F³, secured upon the aforesaid arm F' and bearing upon the pawl F². Pivotedly secured to the end of the arm F' is one end of the operating-lever G. The other end of the operating-lever G is connected to a slotted yoke, H, which is rigidly secured to the crank by set-screws passed through its ends. The lever G is secured to the yoke H by a bolt passed through the end of the lever and the slot of the yoke.

The worm-gear D, hereinbefore mentioned, meshes with two worm-wheels, I J, which are secured upon the piston-rod B' in the manner now to be described. The piston-rod B' is provided with a groove which extends its entire length. The wheel I has a loose center, I', which is provided with a key or rib, I², fitting into the groove in the piston-rod. The wheel I is held to the center I' and the center to the piston-rod by a set-screw, I³, as shown. The worm-wheel J is provided with an internal screw-thread, which, engaging the screw-threaded piston-rod, holds the worm-wheel J in position. The worm-wheels I J are supported by the cover, and are prevented from slipping laterally, and thereby becoming disengaged from the worm-gear D, by an annular shoulder, K, on the top of the cover A², which receives the centrally-raised portion j of the worm-wheel J, which rests upon this shoulder, the wheel I resting upon the wheel J. A triangular plate, L, rests upon the wheel I and prevents the worm-wheels moving upward. Two of its points, L' L², rest upon and are secured to the posts C' C'. The third point, L³, is secured to the cover A² by a bolt passed through the said point and the cover. The two worm-wheels I J are of different sizes, the wheel I having thirty-nine teeth and the wheel J having forty teeth.

In operation the revolution of the crank will impart a circular motion to the upper end of the operating-lever, which motion will be communicated to the ratchet-wheel E through the pawl F². The wheel E being rigidly secured to the worm-gear shaft, the movement

of the said ratchet-wheel will cause the worm-gear to revolve, which, meshing with the worm-wheels I J, will feed the piston B forward and force the lubricant out through the nozzle A' onto the crank. The piston-rod B' fits loosely in the piston B, and is moved forward through the combined action of the gears I J. As hereinbefore mentioned, the gear I has thirty-nine teeth, and the gear J has forty teeth. The gear-wheel I, having but thirty-nine teeth, will revolve faster than the gear-wheel having forty teeth, and the result is, that the piston-rod B' is screwed through the gear-wheel J to the extent of one-fortieth of a turn of the thread in every complete revolution of the two gears. Thus it will be seen that the gear J will gain one tooth during every complete revolution of the two gears, and the piston will move forward a distance equal to one-fortieth of a complete turn of the piston-rod. By loosening the set-screw 13 and turning the hand-wheel B', the piston will rapidly be raised when it is desired to refill the cylinder, and when the piston has reached its lowest point. In lubricators of the class to which mine belongs the lubricating material is generally a thick grease, and it is desirable that the piston should have a slow motion, in order to feed the proper amount of the lubricant to the crank. This slow motion I obtain through the mechanism hereinbefore described.

Having thus described my invention, what I claim, and desire to secure by Letters Patent, is—

35 1. In a lubricator, the combination, with the driving mechanism and the feeding-piston having a screw-threaded piston-rod provided with a groove running its entire length, of two different-sized worm-wheels meshing

with the driving mechanism and secured to the 40 piston-rod, the larger by an internal screw-thread and the smaller by a set-screw and keyed center, substantially as set forth.

2. The combination, with the pitman and the crank, of the lubricator secured upon the 45 pitman by a screw-threaded nozzle, which extends through to the crank, the operating mechanism secured upon the top of the cylinder, consisting of the worm-wheels I and J, and the worm D, having an extended shaft, a 50 ratchet-wheel secured upon the extended portion of the worm-shaft, a sleeve mounted upon the same shaft in juxtaposition to the ratchet-wheel, and having an arm extended past the ratchet-wheel, a pawl pivoted to this arm and held in engagement with the ratchet-wheel by a spring secured to the arm and bearing upon the pawl, and a driving-lever pivotally secured at one end to the end of the arm carrying pawl, and having its other end secured to the crank 55 by a slotted yoke, substantially as specified.

3. The combination, with the cylinder, the feeding-piston, and the driving mechanism comprising a worm-gear shaft and two worm-wheels meshing therewith, of a plate, C, having two posts, C' C', in which the worm-gear is journaled, and a triangular plate, L, resting upon the gear-wheels secured to the top and the posts C' C', and the top having an annular rib, upon which the gear-wheels rest, 65 substantially as described and shown.

In testimony whereof I affix my signature in presence of two witnesses.

WILLIAM S. BEEMAN.
